UNITED STATES PATENT OFFICE

WILLIAM E. WINE, OF TOLEDO, OHIO

HOPPER CAR

Application filed September 8, 1930. Serial No. 480,507.

My invention relates to railway hopper cars and more particularly to wheel hoods which are adapted to be associated with slope or inclined floor sheets of such cars.

5 A principal object of the invention is to provide a wheel hood of simple and rugged construction which may be attached to the slope sheet of the car in such a manner as not to interfere with or retard the flow of 10 lading down the slope sheet.

A primary feature of the invention consists in providing a wheel hood with a top wall having downwardly diverging portions disposed on opposite sides of its longitudinal axis, the top wall being formed with an upwardly projecting rigidifying flange which extends substantially continuously from one end thereof to the other and is disposed adjacent the point of intersection of the diverging portions.

Another feature of the invention consists in providing the interior of the downwardly diverging portions of the top wall of the wheel hood with a plurality of rigidifying flanges.

25 A further feature of the invention consists in providing a wheel hood with a top wall having downwardly diverging portions, the divergence of said portions progressively increasing from adjacent one end of the hood toward the other and said portions being formed on their inner surfaces with downwardly projecting flanges, the portions also being provided adjacent the end of the hood 30 toward which the divergence of said portions increases with relatively short upwardly projecting flanges.

35 A still further feature of the invention consists in providing the slope sheet of the car with upturned flanges adapted to be secured to the wheel hood in overlapping relation to its inner surface.

40 Other and more specific features of the invention residing in advantageous forms, combinations and relations of parts will herein- 45 after appear and be pointed out in the claims.

In the drawings illustrating a preferred embodiment of the invention,—

50 Figure 1 is a fragmentary plan view of a

railway hopper car showing the wheel hood attached to the slope sheet.

Figure 2 is a vertical sectional view taken on line 2—2, Figure 1.

Figure 3 is a plan view of the wheel hood. 55

Figure 4 is a side elevational view of the wheel hood.

Figure 5 is an enlarged sectional view taken on line 5—5, Figure 4 of one-half of the wheel hood. 60

Figure 6 is a view partly in section and partly in elevation taken on line 6—6, Figure 3.

Figure 7 is an enlarged elevational view of one-half of the wheel hood. 65

Figure 8 is an enlarged sectional view of one-half of the wheel hood taken on line 8—8, Figure 4.

Figure 9 is a plan view of a portion of the slope sheet. 70

Figure 10 is a sectional view taken on line 10—10, Figure 9.

Referring more particularly to the drawings, 1 indicates a portion of a slope sheet of a railway hopper car, the sheet forming, as is well known, the inclined bottom of one of the car hoppers. The wheel hood, designated by the reference numeral 2, forms a cover for an opening 3 formed in the slope sheet to permit the upper edge of an adjacent car wheel diagrammatically illustrated at 4 to project above the plane defined by the slope sheet. 75

The wheel hood is preferably formed from cast metal and is provided with substantially vertical side walls 5 and a longitudinally arched top wall 6, the latter terminating in a plane passing through the bottom edges of the side walls. To prevent granular lading, such as coal and the like, from being pocketed in the angle formed by the slope sheet and the upper end of the arched top wall and thereby retarded in its movement down the slope sheet, the top wall is provided on opposite sides of its longitudinal axis with downwardly diverging portions 7. Thus it will be seen that granular lading coming into contact with the upper end of the hood will be deflected on to opposite sides of the latter. 85

90 Since the lower portion of the arched top 95

wall inclines downwardly toward the slope sheet instead of away from it as does the upper portion of the wall, the divergence of the portions 7 progressively increases from 5 adjacent the upper end of the hood toward the lower end and adjacent the latter end they may advantageously merge into one, thereby forming the hood with a substantially flat surface, transverse sections of which 10 are disposed in substantially horizontal planes.

As, when rounding curves, the wheels of a car not only move angularly with respect to the longitudinal axis of the car but also move toward and away from the slope sheet depending upon whether the curve is to the right or to the left, the lower portion of the wheel hood is of greater width than the upper portion. The portions of the side walls 20 6 adjacent the lower end of the hood are, therefore, disposed in substantially parallel planes while from a point intermediate their ends, such as that designated by the reference numeral 8, they converge toward the upper 25 end of the hood.

The portions of the slope sheet bordering the sides of the opening 3 are flanged upwardly as at 9 for attachment to the side walls of the hood and the portions of the 30 slope sheet bordering the ends of the opening are flanged upwardly as at 10 for attachment to the end portions of the top wall of the hood. In order that all of the flanges 35 may be disposed in planes parallel to the respective portions of the hood to which they are adapted to be secured the flanges 9 are disposed in substantially vertical planes while the flanges 10 incline upwardly and inwardly with respect to the axis of the opening. Instead of securing these flanges to the hood in overlapping relation to the exterior thereof they extend upwardly within the hood and are secured thereto in overlapping relation to its interior. In this manner moisture 40 which may be contained in the lading is prevented from seeping downwardly between the hood and the flanges. Although it may be that a small amount of moisture may seep 45 between the flange 10 adjacent the upper end of the opening and the portion of the hood to which it is attached, the inner surface of this portion of the hood may be integrally formed with bosses 11 surrounding the opening 50 through which the attaching rivets 12 pass. Thus it will be seen that only relatively small portions of the flange are in contact with the hood, thereby preventing any substantial corrosion of the slope sheet due 55 to moisture which may seep between the parts in metal to metal contact. The inner faces of the side walls may be formed with an inwardly offset portion 13 to receive the slope sheet attaching flanges 9 and they are also 60 65 preferably formed with lugs or bosses sur-

rounding the apertures 14 through which the attaching rivets extend.

In order that the heads of the rivets will not protrude beyond the outer surface of the side walls and the outer surface of the upper portion of the top wall and thereby impede or retard the flow of lading the outer heads of the rivets passing through these portions of the hood are countersunk. Heretofore it has been customary to provide the wheel hood 75 with laterally projecting flanges for attachment to the slope sheet in the plane of the latter and it has been necessary in this construction to secure the slope sheet and hood together by rivets, the heads of which protrude or extend above the plane of the slope sheet.

Due to the fact that the space between the inner side wall of the hood and the adjacent portion of the car center sill is relatively narrow, it has been found that the flow 80 of lading down the slope sheet between the hood and the center sill is materially retarded and in some cases actually prevented by the upwardly projecting heads of the attaching rivets. In the present construction, however, 85 this difficulty is entirely overcome not only because the outer heads of the rivets are countersunk but also because the rivets are spaced above the planes of the slope sheet.

The top wall of the hood is rigidified by an upwardly projecting flange 15 which preferably extends substantially continuously from one end of the hood to the other adjacent the point of intersection of the downwardly diverging portions 7. The diverging portions are also provided with rigidifying flanges 16 but these flanges are formed on the inner surface of the top wall and extend downwardly therefrom so as not to present 90 obstructions preventing deflection of the lading on to opposite sides of the hood. As may be seen from the drawings, the flanges 16 are disposed on opposite sides of the flange 15 and they preferably terminate short of the ends of the top wall so as not to interfere 95 with the attachment of the flanges 10 thereto. Adjacent the end of the hood toward which the divergence of the portions 7 of the top wall increases the latter is formed with relatively short upwardly projecting flanges 17 100 which are disposed in alinement with and constitute continuations of the downwardly projecting flanges 16. It has been found unnecessary to provide the upper end of the hood with reinforcing flanges similar to the flanges 17 as, due to the cross-sectional shape of this end of the hood, it possesses sufficient 105 rigidity. The hood is also additionally reinforced by a marginal flange 18 which extends around its lower edge and, when the hood is attached to the slope sheet, rests upon the latter. The flanges 15 and 17 which are formed on the exterior of the hood may, as shown, merge into this marginal flange.

From the foregoing it will be perceived 110

that I have provided an integral wheel hood formed with a number of rigidifying flanges which are so arranged that they will not interfere with or retard the flow of lading.

5 Furthermore, the shape of the hood is such that it prevents pocketing of the lading and it is associated with the slope sheet in such manner as to prevent moisture from accumulating between it and the flanges of the slope 10 sheet to which it is attached.

I claim:

1. A cast metal wheel hood for the slope sheet of a railway hopper car, said hood having a top wall provided on opposite sides of its 15 longitudinal axis with downwardly diverging portions, the divergence of said portions progressively increasing from adjacent one end of the hood toward the other, said top wall being integrally formed with longitudinally 20 extending upwardly projecting flanges adjacent the end of the hood toward which the divergence of the said portions of the top wall increase.

2. A cast metal wheel hood for the slope 25 sheet of a railway hopper car, said hood having a top wall provided on opposite sides of its longitudinal axis with downwardly diverging portions, the divergence of said portions progressively increasing from adjacent 30 one end of the hood toward the other, said wall being integrally provided adjacent the intersection of said diverging portions with an upwardly projecting substantially 35 vertical flange extending continuously from end to end of the hood.

3. A cast metal hood for the slope sheet of a railway hopper car, said hood having a top wall provided on opposite sides of its longitudinal axis with downwardly diverging 40 portions, the divergence of said portions progressively increasing from adjacent one end of the hood toward the other, said wall being integrally formed adjacent the intersection of said diverging portions with an upstand- 45 ing substantially vertical flange extending continuously from one end of the hood to the other and with relatively short upwardly projecting flanges arranged on opposite sides of said first named flange and adjacent the 50 end of the hood toward which the divergence of said portions of the top wall increase.

4. A cast metal wheel hood for the slope 55 sheet of a railway hopper car, said hood having a top wall provided on opposite sides of its longitudinal axis with downwardly diverging portions, the divergence of said portions progressively increasing from adjacent one end of the hood toward the other, each 60 of said diverging portions being provided on its interior with a downwardly projecting longitudinally extending flange.

5. A cast metal wheel hood for the slope 65 sheet of a railway hopper car, said hood having a top wall provided on opposite sides of its longitudinal axis with downwardly di-

verging portions, the divergence of said portions progressively increasing from adjacent one end of the hood toward the other, said top wall being integrally provided on opposite sides of the intersection of said diverging portions with downwardly projecting flanges. 70

6. A cast metal wheel hood for the slope sheet of a railway hopper car, said hood having a top wall provided in opposite sides 75 of its longitudinal axis with downwardly diverging portions, the divergence of said portions progressively increasing from adjacent one end of the hood toward the other, said top wall being integrally provided on opposite sides of the intersection of said diverging portions with downwardly projecting flanges and with relatively short upwardly projecting flanges adjacent the end of the hood toward which the divergence of said portions 80 increase. 85

7. A cast metal wheel hood for the slope sheet of a railway hopper car, said hood having a top wall provided on opposite sides 90 of its longitudinal axis with downwardly diverging portions, the divergence of said portions progressively increasing from adjacent one end of the hood toward the other, said top wall being integrally provided on opposite sides of the intersection of said diverging portions with downwardly projecting flanges which terminate short of the ends of the hood, said wall being also provided adjacent the end of the hood toward which the divergence of said portions increase with 95 relatively short upwardly projecting flanges respectively constituting continuations of 100 said downwardly projecting flanges. 105

8. A cast metal wheel hood for the slope sheet of a railway hopper car, said hood having a top wall provided on opposite sides of its longitudinal axis with downwardly diverging portions, the divergence of said portions progressively increasing from adjacent one end of the hood toward the other, said 110 wall being provided on its exterior adjacent the intersection of said diverging portion with a longitudinally extending rigidifying flange and being provided on its interior with a plurality of longitudinally extending 115 rigidifying flanges respectively disposed on opposite sides of said intersection.

9. A cast metal wheel hood for the slope sheet of a railway hopper car, said hood having substantially vertical side walls and an 120 arched top wall, said top wall having downwardly diverging portions and the divergence of said portions progressively increasing from adjacent one end of the hood toward the other, the portions of the side walls adjacent the end of the hood toward which the divergence of said portions of the top wall increase being disposed in substantially parallel planes. 125

10. A cast metal wheel hood for the slope 130

sheet of a railway hopper car, said hood having substantially vertical side walls and an arched top wall, said top wall having downwardly diverging portions and the divergence of said portions progressively increasing from adjacent one end of the hood toward the other, portions of the side walls adjacent the end of the hood toward which the divergence of the said portions of the top wall increase being disposed in substantially parallel planes and portions of the side walls adjacent the other end of said hood converging toward said end.

11. In a railway car, a hopper having a slope sheet provided with an opening above a wheel of the car, a cover for said opening constituting a wheel hood, said cover having substantially vertical side walls and an arched top wall, said slope sheet being provided with upwardly projecting flanges rigidly secured to said side walls in overlapping relation to their inner faces.

12. In a railway car, a hopper having a slope sheet provided with an opening above a wheel of the car, a cover for said opening constituting a wheel hood, said cover having substantially vertical side walls and a longitudinally arched top wall terminating in a plane passing through the lower edges of the side walls, the slope sheet being provided with upturned flanges respectively secured to adjacent portions of the top and side walls of the cover.

13. In a railway car, a hopper having a slope sheet provided with an opening above a wheel of the car, a cover for said opening constituting a wheel hood, said cover having substantially vertical side walls and an arched top wall, the slope sheet being provided with substantially vertical flanges bordering the sides of the opening for attachment to the side walls of the cover and with upwardly and inwardly inclined flanges bordering the ends of the opening for attachment to the top wall of the cover.

14. In a railway car, a hopper having a slope sheet provided with an opening above a wheel of the car, a cast metal cover for said opening constituting a wheel hood, said cover having a peripheral rigidifying rib in engagement with the slope sheet, the latter having upwardly extending flanges disposed within the cover and secured thereto in overlapping relation to its inner surface.

15. In testimony whereof I affix my signature.

WILLIAM E. WINE.
